US00D778567S

(12) **United States Design Patent** (10) Patent No.: **US D778,567 S**
(45) Date of Patent: ** *Feb. 14, 2017

(54) **SHOE INSOLE**

(71) Applicant: **Spenco Medical Corporation**, Waco, TX (US)

(72) Inventors: **David B. Granger**, Lorena, TX (US); **Jacob Martinez**, Temple, TX (US)

(73) Assignee: **Implus Footcare, LLC**, Durham, NC (US)

(*) Notice: This patent is subject to a terminal disclaimer.

(**) Term: **15 Years**

(21) Appl. No.: **29/539,790**

(22) Filed: **Sep. 17, 2015**

(51) LOC (10) Cl. **02-04**

(52) U.S. Cl.

USPC **D2/961**

(58) **Field of Classification Search**

CLAIM

The ornamental design for a shoe insole, as shown and described.

DESCRIPTION

FIG. 1 is a perspective view of a shoe insole showing our new design;

FIG. 2 is a bottom view thereof;

FIG. 3 is a top view thereof;

FIG. 4 is a medial side view thereof;

FIG. 5 is a lateral side view thereof;

FIG. 6 is a front view thereof; and,

FIG. 7 is a back view thereof.

1 Claim, 5 Drawing Sheets
